APPARATUS FOR PRODUCING A HOLLOW ELECTRON BEAM

Harold F. Webster, Schenectady, N. Y., assignor to General Electric Company, a corporation of New York

Application January 12, 1955, Serial No. 481,375

6 Claims. (Cl. 313—157)

My invention relates to apparatus for producing a hollow electron beam and particularly to apparatus for producing such a beam which is well suited for use in high frequency devices.

In electron discharge equipment of the beam type, the cathode and associated electrodes for producing the beam are very important to both the life and the quality of performance of the equipment. In high frequency equipment in which an electron beam is coupled to a conductive structure, it is desirable that the beam be dense, uniform in density and velocity over the cross section of the beam and concentrated essentially at a surface (the surface at which the coupling is to take place). The density of the beam contributes to the strength of the coupling with the high frequency structure while the uniformity and concentration of the beam at a surface contribute to the ability of the beam to produce only the desired excitation of the high frequency structure and thus to the quality of the performance of the equipment.

In accordance with my invention, I provide apparatus including an electron gun which produces a hollow beam having these characteristics and which is further characterized by long life of the emitter (cathode per se). Specifically, I have found that a hollow cathode of proper configuration having an opening therein, when operated in a highly evacuated envelope, tends to produce a hollow beam of electrons, that is, a beam in which substantially all of the electrons are concentrated in an annulus corresponding in shape and size to the opening. By immersing the cathode in a magnetic field parallel in direction to the beam produced, the relatively low electron density in the center of the beam is reduced to a negligible value leaving a rather clearly defined annular beam having a total current substantially equal to that produced without the magnetic field. My invention also includes the provision of means for minimizing the emission of electrons from the exterior of the hollow cathode which would tend to prevent the production of a well-defined hollow electron beam.

It is an object of my invention to provide a new and improved electron discharge apparatus for producing a hollow electron beam.

It is a further object of my invention to provide an electron gun characterized by longer operating life and improved electron beam producing characteristics.

Further objects and advantages of my invention will become apparent as the following description proceeds, reference being had to the accompanying drawing and its scope will be pointed out in the appended claims. In the drawing, Fig. 1 is a longitudinal view in section of electron discharge apparatus embodying my invention, and Fig. 2 illustrates schematically a transverse section of the electron beam produced by the apparatus of Fig. 1.

Referring now to the drawing, I have shown my invention embodied in electric discharge apparatus of the beam type and including a highly evacuated cylindrical envelope 1 in which the electrodes are mounted in spaced

2

relation along the axis thereof. An electron source is provided by a cathode member 2 which is in the form of a hollow cylinder closed at its lower end by plate 3. In its preferred form, the upper end is an outwardly extending conical portion 4 which is truncated to provide a relatively small centrally located circular opening 5. The interior wall of the cathode body or at least the portion of the wall surrounding the opening 5 is coated with a suitable electron emission enhancing coating of a type well known in the art.

In the preparation of the cathode, the emitting materials, such as one or more of the alkaline earth oxides, are mixed with a suitable binder or carrier to form a slurry which is introduced into the cathode through the opening 5. The slurry is spread around and the excess poured off to leave a layer 6 of the emitting material on the interior surface of the cathode cylinder and particularly on the inner surface of the conical portion.

In order to raise the temperature of the cathode 2 sufficiently to produce thermionic emission from the coating 6, I provide a suitable resistance-type heater enclosing the cathode cylinder 2 and illustrated schematically by the heater wires 7. These wires are enclosed in a suitable heat conserving shield 8 which is generally cup-shaped to conform with the shape of the heater. As illustrated, the heater is insulated from both the shield 8 and the cathode 2 by refractory insulating material 9. The cathode assembly thus far described is supported from a plurality of lead-in conductors 10 sealed through a press 11 in the lower end of the envelope 1 by conductors 12-14, inclusive. Conductor 12 supports the cathode 2 and conductors 13 and 14 are joined to opposite ends of the heater wire 7. As is apparent from the drawing, the conductor 14 is also bonded to the heat shield 8 to provide mechanical support and to connect it electrically with one end of the heater.

An accelerating electrode or anode 15 is supported from the remaining lead-in conductor 10 by conductor 16. Specifically anode 15 is annular in shape and is supported in parallel relation to the plane of the cathode opening 5 and with the opening 17 therein in alignment with opening 5.

As a means of minimizing the emission of electrons from the exterior of the cathode 2, I provide an electrostatic shield 18 between the cathode and anode which operates at cathode potential and at a substantially lower temperature than the cathode. The shield is in the form of an annular member 18 mounted between the anode and cathode and supported from the same conductor 12 which supports the cathode 2. The opening 19 in the shield is a little larger than the end of the cathode so that the conduction of heat to the shield is minimized. It is apparent that the shield 18 is electrostatically a part of the cathode structure extending outwardly in essentially the same plane as the opening 5 of the cathode. It is also apparent that the shield may be supported directly from the conical portion of the cathode by a material having relatively low thermal conductivity to provide the desired lower operating temperature of the shield 18.

At the opposite end of the envelope 1, a collector electrode 20 is supported in alignment with the openings in the cathode 2, shield 18 and anode 15 by means of lead-in conductor 21. A suitable high frequency conductive structure 22 is supported between the anode 15 and collector 20 for interaction with the electron beam. As illustrated, this structure may be the helix of a traveling wave tube.

Means for collimating the electrons of the beam are provided by an electromagnet including a cylindrical support 23 of insulating material and a coil illustrated schematically at 24. In accordance with the present

invention, the field produced by the electromagnet also cooperates with the cathode to produce a hollow beam of electrons. It is apparent that, for the coil 24 to be effective for this latter purpose, the shield 8 and the cathode body must be non-magnetic under operating conditions. This may be accomplished by utilizing non-magnetic material, such as tantalum or metal which becomes non-magnetic at a temperature lower than its normal operating temperature. In accordance with one form of the device on which tests were conducted, the shield 8 was formed of molybdenum and the cathode of nickel which becomes non-magnetic at 360° C. Since the operating temperature of the cathode is in the order of 800° C., it is clear that the cathode structure as a whole is not self-shielding with respect to the magnetic field under operating conditions.

As will be readily understood by those skilled in the art, the tube may be operated by the application of suitable potential to the conductors 10 and 21 to heat the cathode and to accelerate the electrons toward the collector electrode 21. For example, the anode 15 and collector electrode 20 may be maintained at a voltage in the order of 100 to 1000 volts D. C. with respect to the cathode 2 and the shield 18. The magnetic field may be in the order of 100 to 300 gauss.

With this construction, electrons emitted from the interior of the cathode are accelerated toward the collector 21 in a beam having an exterior corresponding generally to the shape and size of the opening in the cathode. Without the magnetic field and with the configuration of the cathode and shield illustrated, the density of the electrons is much lower in the center than it is toward the outer surface of the beam. The electrons from the center, however, tend to have a higher velocity than those at the outer edge and these are accordingly undesirable. When the cathode is combined with the axial magnetic field, the electrons in the central portion of the beam are essentially eliminated and the total current of the beam has substantially the same total value as it does without the magnetic field. Accordingly, the combination provided by this invention results in a rather well-defined annular beam of high current density and uniform velocity at a given cross section. The hollow cathode, of course, has the advantages previously observed with respect to hollow emitting structures, namely, that of conserving the emission enhancing material, minimizing the contamination of the other parts with this material and also minimizing the contamination of the emitting material by any material driven off from the other electrodes during operation of the device.

While I have shown and described a particular embodiment of my invention, it will be apparent to those skilled in the art that modifications may be made without departing from my invention and I, therefore, aim by the appended claims to cover any such modifications as fall within the true spirit and scope of my invention.

What I claim as new and desire to secure by Letters Patent of the United States is:

1. Apparatus for producing a hollow beam of electrons comprising an evacuated envelope, a plurality of electrodes including a cathode, an anode having an opening therethrough and a collector electrode supported in alignment within said envelope in the order named, said cathode comprising a hollow conductive member having an aperture in the side thereof toward said anode with a maximum dimension substantially less than the maximum transverse dimension of said cathode to provide an internal surface around said aperture facing away from said anode, an electron emission enhancing coating on said internal surface, means for heating said cathode and means surrounding at least said anode and said cathode for producing a magnetic field parallel to the path between the aperture in said cathode and said collector, said cathode being non-magnetic under operating conditions so that said magnetic field extends within said cathode.

5 2. Apparatus for producing a hollow beam of electrons comprising an evacuated envelope, a plurality of electrodes including a cathode, an anode and a collector electrode supported within said envelope in spaced relation along the path of the electron beam to be produced and in the order named, said cathode comprising a hollow cylindrical member with a conical end facing said anode, said end being truncated to provide a small centrally located opening, an electron emission enhancing coating on the interior surface of said end surrounding said opening, means for heating said cathode to a temperature sufficient to produce emission from said coating and to render said cathode non-magnetic, and means surrounding said cathode for producing a magnetic field within said cathode parallel to the axis thereof.

10 3. Apparatus for producing a hollow beam of electrons comprising an evacuated envelope, a plurality of electrodes including a cathode, an anode and a collector electrode supported with said envelope in spaced relation along the path of the electron beam to be produced in the order named, said cathode comprising a hollow cylindrical member with an end sloping inwardly and toward said anode and defining a small centrally located opening, an electron emission enhancing coating on the interior surface of said end surrounding said opening, means for heating said cathode to a temperature sufficient to produce emission from said coating, said cathode being non-magnetic under operating conditions, and means surrounding said electrodes for producing a magnetic field within said cathode parallel to the axis thereof.

15 4. An electron gun for producing a hollow electron beam comprising a hollow cylindrical cathode having an outwardly extending conical end, said conical end being truncated to provide a centrally located opening therein, an electron emission enhancing coating on the interior surface of said end surrounding said opening, a planar conductive member supported adjacent said end in heat insulated relation with respect to said cathode and having an aperture registering with the aperture in said end, said member being electrically connected to said cathode and an apertured anode supported in parallel and spaced relation with respect to said planar member.

20 5. A hollow cathode comprising a hollow cylindrical member with an end sloping inwardly and toward said anode and defining a small centrally located opening, an electron emission enhancing coating on the interior surface of said end surrounding said opening, means for heating said cathode to a temperature sufficient to produce emission from said coating, and a planar shield member supported in perpendicular relation to the axis of said cylindrical member in substantially the plane of said opening and forming electrically a part of said cathode.

25 6. A hollow cathode comprising a hollow cylindrical member with an end sloping inwardly and toward said anode and defining a small centrally located opening, an electron emission enhancing coating on the interior surface of said end surrounding said opening, means for heating said cathode to a temperature sufficient to produce emission from said coating, an apertured planar shield member, and means supporting said shield member from said cylindrical member in perpendicular relation to the axis thereof in substantially the plane of said opening and said last-mentioned means conducting a minimum of heat from said cylindrical member to said shield member.
